UNITED STATES PATENT OFFICE

JOSEPH N. TROXELL, OF NORTH CATASAUQUA, PENNSYLVANIA

HORSESHOE

Application filed May 18, 1928. Serial No. 278,760.

The invention aims to provide a new and improved construction of horseshoe, in which novel provision is made whereby the rear portion thereof may vertically spring, providing 5 adequate protecting means for the animal's hoof, to prevent soreness from continuous treading upon hard pavements.

With the foregoing in view, the invention resides in the novel subject-matter herein-10 after described and claimed, description being accomplished by reference to the accompanying drawing.

Fig. 1 is a bottom plan view,
Fig. 2 is an edge view,
15 Fig. 3 is a rear end elevation, and
Fig. 4 is a horizontal sectional view on line 4—4 of Fig. 2.

In the drawing above briefly described, the numeral 5 denotes a horseshoe preferably hav-20 ing the usual hoof-engaging lip 6 at its front end and equipped at said end with a calk or calks 7. Preferably, two of these calks are used, having tapered studs 8 driven into open-25 ings in the shoe, said calks being held in place by the existing friction between the studs 8 and the walls of the openings, so that they may be removed when it is desired to substi-30 tute new calks. To prevent turning of the calks, an abrupt shoulder 9 has been shown at the lower side of the shoe.

The rear ends of the shoe 5 terminate in vertically yieldable spring fingers 10 whose upper sides are preferably spaced below the plane in which the upper side of the shoe 35 body is disposed. The lower sides of these spring fingers are by preference in a plane above that in which the lower side of the shoe body is disposed. The fingers 10 vertically yield each time the horse or other animal places his weight upon the shoe, and hence they effectively absorb shocks and prevent soreness.

In thus spacing the spring fingers, the upper and lower sides of the rear ends of the shoe are cut away or forged and upper and lower shoulders are thereby formed at the inner ends of the fingers, which serve to resist forward pressure or thrust of the heel portion of the pad, hereinafter described. 45 The lower shoulder is preferably square or

more abrupt than the upper shoulder to more firmly resist the greater thrust or forward pressure of the lower part of the heel portion of the pad.

A flat pad 11 preferably formed of vul-55 canized rubber and reinforcing fabric, lies upon the upper side of the shoe 5 and at its rear end is provided with a downwardly projecting resilient heel 12 which is integral with said pad and whose lower side is below 60 the lower side of the shoe. This heel 12 is formed with recesses 13 which snugly receive the spring fingers 10 so that portions of the heel are below these fingers and other portions thereof above them. Not only do the 65 fingers 10 yield, but the heel 12 also resiliently absorbs shocks, so that there is no danger of the animal's feet becoming sore, even when he must tread continually upon hard surfaces. 70

The shoe 5 is formed of a good grade of steel with at least its rear end tempered to provide the spring fingers 10. The pad 11 and the heel 12 are of appropriate vulcanized rubber, and at least the pad is reinforced 75 with fabric or other adequate material.

I claim:

1. A horseshoe whose rear ends terminate in vertically yieldable spring fingers disposed in a plane below the plane of the upper side 80 and above the plane of the lower side of the shoe, and a pad lying upon the shoe and having a downwardly projecting resilient heel whose lower side is below the lower side of the shoe, said heel having recesses receiving said 85 spring fingers.

2. A horseshoe having the upper and lower sides of its rear ends cut away to form vertically yieldable spring fingers, said fingers having their upper sides below the upper side 90 of the shoe body and their lower sides above the lower sides of the shoe body, thereby forming upper and lower shoulders at the inner ends of the upper and lower sides of the spring fingers, said lower shoulder being 95 square to provide an abrupt stop for a heel pad.

In testimony whereof I have hereunto affixed my signature.

JOSEPH N. TROXELL. 100
